ATTORNEY

UNITED STATES PATENT OFFICE.

HENRY L. JENNINGS, OF SWARTHMORE, PENNSYLVANIA, ASSIGNOR TO WESTINGHOUSE ELECTRIC & MANUFACTURING COMPANY, A CORPORATION OF PENNSYLVANIA.

GOVERNOR.

Application filed September 8, 1924. Serial No. 736,648.

My invention relates to governing apparatus, more particularly to that class of apparatus employing a fluid pressure, varying as a function of the speed of the machine governed, as the actuating medium, and has for its object the provision of apparatus of the character designated which shall be simple of construction, reliable in operation and shall be readily adjustable for different operating conditions.

In the applications of Henry F. Schmidt, Serial No. 580,378, filed August 7, 1922, No. 604,032, filed November 29, 1922, now Patent 1,533,766 dated April 14, 1925, and 15 737,396, filed Sept. 12, 1924, now Patent 1,533,767 dated April 14, 1925, all assigned to the Westinghouse Electric and Manufacturing Company, there is described a variable fluid pressure governor having an element actuated by the variable fluid pressure in opposition to the force exerted by a spring. Means are shown wherein a comparatively wide range of governing movement is attained for a given deflection of the 20 spring, and means are also shown for varying the comparatively wide range of movement aforesaid so as to provide a varying area of opening of the admission valve of the prime mover per unit of change in governing pressure.

The particular object of my invention is to provide improved apparatus of the character described in the applications aforesaid, simpler in design, easy to manufacture and readily adjustable whereby it may be adapted to widely varying conditions.

Apparatus embodying features of my invention is illustrated in the accompanying drawings in which Fig. 1 is a view, partly 40 in section, showing my improved governing apparatus applied to a steam turbine and Figs. 2, 3, and 4 are detail views, drawn to a larger scale, of parts of the apparatus.

In the design of governing apparatus 45 wherein the force of variable fluid pressure is employed to actuate an element in opposition to the force exerted by a spring, difficulties have been encountered due to the fact that a spring of sufficient strength to act in direct opposition to the variable fluid pressure, and of the scale required to deflect suffi-

ciently to provide ample governing movements is of inordinate size and length, rendering its use impractical.

It has also been found desirable to provide 55 a governing apparatus for controlling the admission valve to a steam driven prime mover wherein there is a constant rate of valve opening during a limited range of movement, and thereafter a varying rate of 60 opening to compensate for the varying rate of flow of steam through the valve at low ratios of pressure between the inlet and exit sides thereof. At times when the pressure on the exit side of the admission valve is less 65 than .57 of the pressure on the inlet side thereof, the steam flow through the valve increases directly with its opening area. When the pressure on the exit side of the valve increases beyond .57 of the pressure 70 on the inlet side, the flow thereby does not increase directly with the area of the opening and a relatively wider opening of the valve is necessary to secure a direct increment in the flow of steam thereby. 75

In accordance with my invention I provide a variable fluid pressure governing apparatus having an element actuated by the fluid under pressure in opposition to the force exerted by a spring in which is incorporated 80 a simple follow-up mechanism providing a comparatively wide range of movement of the element for a given deflection of the spring. I also provide means whereby, at a predetermined point in the valve travel, 85 its rate of movement per unit of change in governing pressure and consequent unit of change in spring deflection may be varied. I accomplish this by providing a supporting member for the spring, retain the supporting 90 member from a stationary support at one side of the spring, and provide means movable with the element for supporting the other side of the member.

Referring now to the drawings for a better 95 understanding of my invention, I show in Fig. 1 a steam turbine 10 having an admission valve 11 controlled by my improved governing apparatus at 12. The governing apparatus at 12 is actuated by fluid under 100 pressure varying with the speed of the prime mover 10, developed by a centrifugal pump

13, driven by a shaft 14 of the turbine 10. Fluid, usually lubricating oil, is supplied to the inlet side of the pump from a reservoir 16 and is delivered through a conduit 17 to the governing apparatus. The governing apparatus comprises a governor casing 18, having a cylindrical upper portion defining an operating cylinder 19 in which an operating piston 21 is disposed. The operating piston 21 is hollow and is provided with tubular extensions 22 and 23 at its top and bottom, respectively. The top extension 22 is provided with a vent hole 25 so that fluid leaking into the upper portion may drain off. The operating piston 21 is provided with upper and lower admission ports 24 and 26 and an exhaust port 27 by means of which ports the governing fluid pressure may be admitted above or below the piston 21 to move it down or up in the cylinder 19, or to maintain it stationary, as is well understood in the art to which my invention relates.

The admission of fluid to the ports 24 and 26 is controlled by a tubular pilot valve 28, said pilot valve being disposed within the hollow portion of the piston 21 and being provided with suitable upper and lower ports 31 and 33. The pilot valve 28 is also provided on its outer surface with an exhaust passage 32, affording communication between either of the piston ports 24 or 26 and the exhaust port 27. The pilot valve 28 is closed at its upper end by a head member 33, which serves as the lower abutment for a spring 34. An upward movement of the pilot valve 28 places ports 31 and 26 in communication, admitting fluid under pressure beneath the operating piston 21 and places ports 24 and the exhaust cavity 32 and port 27 in communication exhausting fluid from above the operating piston 21 so that it moves upwardly, following the pilot valve. Upon a downward movement of the pilot valve, fluid under pressure is admitted above the piston 21 and fluid is exhausted from beneath the piston 21 so that it moves downwardly. Any movement of the pilot valve 28 is followed by an equal movement of the piston 21 until the ports 24 and 26 are covered, when the piston 21 will remain stationary until another movement of the pilot valve 28 takes place.

The operating piston 21 is provided at its upper end with an extended portion 36, to the upper end of which is attached a rod 37 for actuating the admission valve 11. The spring 34 is located within the extended portion 36 and has an upper abutment 38 carried by a lever 39. The upper abutment 38 is provided with an adjusting nut 41 by means of which the compression of the spring 34 may be varied and thus adjust the speed of the prime mover. The load on the spring 34 is such that at normal load on

the turbine, and consequent normal speed and governing pressure, it will just withstand the pressure acting against the pilot valve 28.

The lever 39, against which the movable abutment 38 bears, is pivoted at 42 on an arm carried by the extension 36 of the piston 21. The opposite end of the lever bears against a fulcrum member 43 carried by a fixed support 44 extending upwardly from the governor casing 18. That part of the lever 39 between the fulcrum member 43 and the abutment 38 will be hereinafter referred to as lever arm or distance *a* while that part of the lever between the abutment 38 and the pivot 42 will be hereinafter referred to as lever arm or distance *b*.

The support 44 is provided with a slot 46 and the fulcrum member 43 is provided with a threaded bolt 47, fitting into the slot 46 and having an adjusting nut, whereby its position relative to the lever arm *a* may be changed either vertically or horizontally.

The fulcrum member 43 has a flat surface 48 and a curved surface 51, which coincide at the edge 52 against which the lever arm *a* bears during a limited range of movement of the operating piston 21, and limited opening of the admission valve 11. Thereafter it bears against the curved surface 51, increasing the effective length of the lever arm *a* upon downward movements of the operating piston, and decreasing it upon upward movements of the operating piston. This serves to vary the range of movement of the admission valve in a manner to be more fully described later.

The operation of the apparatus is as follows: Fluid under pressure varying with the speed of the turbine 10 is developed by the pump 13 and delivered to the governing apparatus 12 and to the interior of the pilot valve 28 through the conduit 17. Upon an increase in speed, and consequent increase in governing pressure, the force exerted by the spring 34 is overcome and the pilot valve 28 is moved upwardly followed by the operating piston 21 in a manner already described. As the pilot valve 21 moves upwardly it further compresses the spring 34, which compression is partly offset by the upward movement of the operating piston 21 carrying with it the end of the lever 39 at the pivot 42, thus permitting an upward movement of the movable abutment 38. Inasmuch as the other end of the lever is bearing on the fixed fulcrum 43, the movable abutment 38 is held back by the lever and the spring 34 is compressed in the upward movement of the operating piston. The extent of this upward movement of the piston 21 per unit of deflection of the spring 34 may be determined by a consideration of the following:

The pilot valve 28 and the piston 21 move

upwardly until they assume their normal position relative to each other, that is, until the ports 24 and 26 are again covered. It will be clear that the pivot 42 therefore moves upwardly the same distance as the pilot valve 28, and that the deflection of the spring 34 is equal to the difference in movement of the abutment 38 and the pivot 42.

The movement of the pivot 42 may now be determined by the simple law of the lever which states that each part of the lever moves a distance proportional to its distance from the fulcrum. Likewise, the difference in movement of any two parts bears the same proportion to the difference of their distances from the fulcrum, which is their distance from each other. Applying this law, the movement of the pivot 42 is to the distance $a+b$ as the movement of the abutment 38 is to the distance a . Also, the difference in movement of the pivot 42 and the abutment 38 to the difference of their distances from the fulcrum 43 (the distance b) is in the same proportion. Therefore the movement of the pivot 42 is to the difference of movement of the pivot 42 and the abutment 38 as the distance $a+b$ is to the distance b . In other words, the movement of the piston 21 per unit of deflection of the spring 34 is the ratio of the distance $a+b$ to the distance b .

The movement of the piston 21 per unit of deflection of the spring 34 may be increased by increasing the distance a , since this increases the proportion $a+b$ to b ; and it may be decreased by shortening the distance a , which decreases the proportion $a+b$ to b .

Assume, for illustration, that lever arms or distances a and b are equal, in which case the distance $a+b$ is twice the distance b , and that there is an increase in governing pressure forcing the pilot valve upwardly causing a deflection of the spring 34 one unit; the piston 21, following the movements of the pilot valve 28, moves upwardly taking with it the pivot 42 of the lever, until it has moved one unit more than the abutment 38. This difference of movement provides for the one unit of deflection of the spring 34, permitting the pilot valve 28 to resume its normal position relative to the piston 21, in which the ports 24 and 26 are closed. The pivot 42 moves upwardly two units since the distance $a+b$ in this case is twice the distance b . The movement of the piston 21 is therefore twice the deflection of the spring 34.

By the adjustment feature heretofore described, the length of the arm a , and hence the relative lengths of the lever arms a and b may be varied, and the movement of the operating piston per unit of deflection of the spring 34 may be varied so as to effect any desired governing movement per unit

of deflection of the spring 34. Increasing the length of the lever arm a increases the governing movement per unit of deflection of the spring 34 and decreasing the length thereof decreases said movement. Furthermore raising or lowering of the fulcrum member 43 serves to adjust the speed of the machine governed.

Upon an increase in load, and a consequent decrease in speed of the turbine 10, the pressure developed by the pump 13 decreases and the force of the spring 34 causes the pilot valve 28 to move downwardly followed by the operating piston 21 and the end of the lever at the pivot 42, the action of the apparatus being opposite to that just described for an upward movement of the operating piston. During a limited range of movement of the operating piston 21 and a limited opening of the admission valve 11, the lever arm a bears on the edge 52 of the fulcrum member 43 and the unit of movement of the operating piston 21 per unit of deflection of the spring 34 is constant. Upon a further increase in load and consequent decrease in speed, requiring a wider opening of the admission valve to effect a direct increment in the steam admitted to the turbine, the lever arm a bears upon the curved surface 51 of the cam fulcrum member 43. In this position the lever arm a is lengthened, and a relatively greater movement of the operating piston per unit of deflection of the spring 34 is effected.

By means of the adjusting bolt 47 the cam member 43 may be adjusted vertically and thus adjust the point of opening of the admission valve 11 when the lever begins to bear on the curved surface 51 of the cam member 43. Vertical adjustment of the cam member 43 would affect the speed of the prime mover, but this effect may be neutralized by a counter adjustment of the adjusting nut 41 to maintain the proper spring compression. Further downward movement of the operating piston 21 beyond the above mentioned point results in lengthening the arm a and increasing the movement of the operating piston per unit of deflection of the spring 34. This action should take place at that point when the pressure at the exit side of the admission valve 11 is .57 of the pressure at the inlet side thereof. Upon a further reduction in speed of the prime mover, requiring a further increment of steam thereto, the movement of the operating piston 21 and the admission valve 11 is comparatively more per unit of deflection of the spring 34, and the area of opening of the admission valve made comparatively greater in order to effect a direct increment of steam flow by the admission valve 11.

From the foregoing it will be apparent that I have invented an improved variable

fluid pressure governing apparatus, simple of design and operation, wherein a comparatively wide range of movement per unit of deflection in the spring element thereof is secured, and wherein a varying rate of opening of the admission valve is obtained per unit of change in governing pressure.

While I have shown my invention in but one form, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. In a variable fluid pressure operated governing apparatus, the combination of a pilot valve actuated by the variable fluid pressure, an operating piston controlled by the pilot valve and following its movements, a spring associated with the pilot valve for opposing the variable fluid pressure, a movable abutment for the spring, a lever controlling the movable abutment, means carried by the operating piston supporting one end of the lever, and means carried by a stationary member for supporting the opposite end of the lever.

2. In a variable fluid pressure operated governing apparatus, the combination of a pilot valve actuated by the variable fluid pressure, an operating piston controlled by the pilot valve and following its movements, a spring associated with the pilot valve for opposing the variable fluid pressure, said spring being disposed between the pilot valve and a movable abutment, a lever controlling the movable abutment, said lever being disposed between a fulcrum carried by a stationary member and means carried by the operating piston, and means for adjusting movements of the movable abutment relative to the movements of the operating piston.

3. In a variable fluid pressure operated governing apparatus, the combination of an element actuated by the variable fluid pressure, a spring coacting at one end with the element for opposing the variable fluid pressure, a supporting member coacting with the other end of the spring, means movable with the element for retaining the supporting member at one side of the spring, and stationary means for retaining the member at the opposite side.

4. In a variable fluid pressure operated governing apparatus, the combination of an element actuated by the variable fluid pressure, a spring coacting at one end with the element for opposing the variable fluid pressure, an abutment coacting with the other end of the spring, a member supporting the abutment, means movable with the element

for retaining the member at one side of the spring and stationary means for retaining the member at the opposite side.

5. In a variable fluid pressure operated governing apparatus, the combination of an element actuated by the variable fluid pressure, a spring coacting at one end with the element for opposing the variable fluid pressure, an abutment coacting with the other end of the spring, a lever, means for attaching the abutment to an intermediate point on the lever, a fixed fulcrum member for one end of the lever, and means movable with the element for supporting the other end of the lever.

6. In a variable fluid pressure operated governing apparatus, the combination of a pilot valve actuated by the variable fluid pressure, an operating piston controlled by the pilot valve and following its movements, a spring associated with the pilot valve and having one end secured thereto for opposing the variable fluid pressure, an abutment for the other end of the spring, a lever for supporting the abutment, means movable with the operating piston for supporting one end of the lever, and a stationary member for supporting the other end.

7. In a variable fluid pressure operated governing apparatus, the combination of a pilot valve actuated by the variable fluid pressure, an operating piston controlled by the pilot valve and following its movements, a spring associated with the pilot valve and having one end secured thereto for opposing the variable fluid pressure, a lever, an abutment for the other end of the spring positioned midway between the ends of the lever, means movable with the operating piston for supporting one end of the lever, a stationary member for supporting the other end of the lever, and means for varying the relative lengths of the lever arms.

8. In a variable fluid pressure operated governing apparatus, the combination of a pilot valve actuated by the variable fluid pressure, an operating piston controlled by the pilot valve and following its movements, a spring associated with the pilot valve and having one end secured thereto for opposing the variable fluid pressure, a lever, an abutment for the other end of the spring positioned midway between the ends of the lever, means movable with the operating piston for supporting one end of the lever, a stationary member for supporting the other end of the lever, and means for varying the position of the stationary member.

9. In a variable fluid pressure operated governing apparatus, the combination of a pilot valve actuated by the variable fluid pressure, an operating piston controlled by the pilot valve and following its movements, a spring associated with the pilot valve and having one end secured thereto for oppos-

ing the variable fluid pressure, a lever, an abutment for the other end of the spring positioned midway between the ends of the lever, means movable with the operating 5 piston for supporting one end of the lever, a stationary member for supporting the other end of the lever, and means for varying the position of the stationary member longitudinally and laterally with respect to 10 the spring.

10. In a fluid pressure governing apparatus, the combination of an operating piston, an element responsive to fluid pressure and having means controlling the movements of 15 the operating piston, a fulcrum member, a lever having one point movable with the operating piston and a second point held against movement by the fulcrum member, and a spring acting between said lever, at a 20 third point, and said pressure-responsive element, said second point of the lever being at least twice as far from the first point as said third point is from said first point.

11. In a fluid pressure governing apparatus, the combination of an operating piston, an element responsive to fluid pressure and having means controlling the movements of the operating piston, a fulcrum member, a lever having one point movable by the piston and a second point held against movement by the fulcrum member, and a spring acting between said lever, at a point intermediate the two first-mentioned points, and said pressure-responsive element, the pressure exerted by said spring on said pressure-responsive element being equal to the fluid pressure acting thereon.

12. In a fluid-pressure governing apparatus, the combination of an operating piston, 40 a pilot valve controlling the admission of motive fluid to said operating piston, pressure-responsive means for actuating said pilot valve, a fulcrum member, a lever movable by the piston at one point and held 45 against movement by the fulcrum member at a second point, and a spring acting between the lever, at a third point, and the pressure-responsive element, said second point being spaced at least twice as far from the first 50 point as the third point is from said first point.

13. In a fluid-pressure governing apparatus, the combination of an operating piston, a pilot valve controlling the admission of 55 motive fluid to said operating piston, pressure-responsive means for actuating said pilot valve, a fulcrum member, a lever movable by the piston at one point and held against movement by the fulcrum member 60 at a second point, and a spring acting between the lever, at a third point, and the pressure-responsive element, said spring exerting a force equal to the fluid pressure acting on said pressure responsive element.

14. In a fluid-pressure governing appara-

tus, the combination of an operating piston, a pilot valve controlling the admission of motive fluid to said operating piston, a fulcrum member, a lever held against movement at one point by the fulcrum member 70 and movable by the operating piston at another point, said pilot valve constituting a fluid pressure-responsive element, and a spring acting between the pilot valve and said lever at a point intermediate the two 75 first-mentioned points, the pressure exerted by said spring on said pilot valve being equal to the fluid pressure acting thereon.

15. In a fluid pressure governing apparatus, the combination of an operating piston 80 having a hollow portion, a pilot valve disposed within the hollow portion and controlling the movements of the piston, pressure-responsive means for actuating the pilot valve, a spring attached at one end to 85 said pressure-responsive means, and a lever for supporting the other end of the spring, said lever being movable with the operating piston at one side of the spring and held against movement at the opposite side of the 90 spring.

16. In a fluid pressure governing apparatus, the combination of an operating piston, a stationary element having a hollow portion in which the piston operates, one of said 95 elements having ports through which motive fluid is admitted to actuate the operating piston, a pilot valve controlling the flow of motive fluid through said ports, means responsive to fluid pressure and actuating the 100 pilot valve, a lever movable at one point by the operating piston and held against movement at another point by the stationary element, and a spring acting between the lever, at a third point, and the pressure-responsive 105 means, said spring exerting a force on said pressure-responsive means equal to the fluid pressure acting thereon, and said third point being disposed as near to that one of the two first-mentioned points of the lever which 110 coacts with the element having the ports as to the other of said two points.

17. In a variable fluid pressure operated governing apparatus, the combination of a pilot valve actuated by the variable fluid pressure, an operating piston controlled by the pilot valve and following its movements, a spring associated with the pilot valve for opposing the variable fluid pressure, said spring being disposed between the pilot valve 115 and a movable abutment, a lever controlling the movable abutment, means carried by the operating piston supporting one end of said lever, and a fulcrum for the opposite end of said lever carried by a stationary member, 120 said fulcrum permitting a varying relative rate of movement between the operating piston and the movable abutment.

18. In a variable fluid pressure operated governing apparatus, the combination of a 125

1. pilot valve actuated by the variable fluid pressure, an operating piston controlled by the pilot valve and following its movements, a spring associated with the pilot valve for opposing the variable fluid pressure, said spring being disposed between the pilot valve and a movable abutment, a lever controlling the movable abutment, one arm of said lever being carried by the operating piston, and a cam member carried by a stationary element forming a fulcrum for the other arm of said lever, said cam member having an angular edge and a curved surface, the angular edge providing a substantially constant radius of movement for the lever arm during a limited range of movement of the operating piston and the curved surface thereafter varying the radius of movement.
2. 19. In a variable fluid pressure operated governing apparatus, the combination of a pilot valve actuated by the variable fluid pressure, an operating piston controlled by the pilot valve and following its movements, a spring associated with the pilot valve for opposing the variable fluid pressure, said spring being disposed between the pilot valve and a movable abutment, a lever controlling the movable abutment, one arm of said lever being carried by the operating piston, a cam member supported by a stationary element forming a fulcrum for the other arm of said lever, said cam member having an angular edge and a curved surface, the angular edge providing a substantially constant radius of movement for the lever arm during a limited range of movement of the operating piston and the curved surface thereafter varying the radius of movement, and means for adjusting the position of said cam member so as to increase or decrease the substantially constant radius of movement of the lever arm.
3. 20. In a variable fluid pressure operated governing apparatus, the combination of a pilot valve actuated by the variable fluid pressure, an operating piston controlled by the pilot valve and following its movements, a spring associated with the pilot valve for opposing the variable fluid pressure, said spring being disposed between the pilot valve and a movable abutment, a lever controlling the movable abutment, one arm of said lever being carried by the operating piston, and a cam member carried by a stationary element forming a fulcrum for the other arm of said lever, said cam member having an angular edge and a curved surface, the angular edge providing a substantially constant radius of movement for the lever arm during a limited range of movement of the operating piston and the curved surface thereafter varying the radius of movement, and means for adjusting the position of said cam member so as to increase or decrease the substantially constant radius of movement of the lever arm.
4. 21. In a variable fluid pressure operated governing apparatus for a prime mover having an admission valve, the combination of a pilot valve actuated by the variable fluid pressure, an operating piston controlling the opening and closing of the admission valve, said operating piston being controlled by the pilot valve and following its movements, a spring between the pilot valve and a movable abutment, a lever controlling the movable abutment, one arm of said lever being carried by the operating piston, a cam member supported by a stationary element forming a fulcrum for the other arm of said lever, said cam member having an angular edge and a curved surface, the angular edge providing a substantially constant radius of movement for the lever arm during a limited range of movement of the operating piston and the curved surface thereafter varying the radius of movement, and means for adjusting the position of said cam member so as to increase or decrease the substantially constant radius of movement of the lever arm, means for adjusting the position of said cam member so as to increase or decrease the substantially constant radius of movement of the lever arm, means for adjusting the position of said cam member so as to increase or decrease the initial length of said lever arm, and means carried by the movable abutment for adjusting the compression of the spring.

In testimony whereof, I have hereunto subscribed my name this second day of September, 1924.

HENRY L. JENNINGS.
